COMBINED MUFFLER AND AIR HEATER

Application filed August 14, 1928. Serial No. 299,617.

The present invention relates to improvements in combined mufflers and air heaters capable of being installed upon motor driven vehicles and particularly, the closed type, whereby the exhaust from the engine of the vehicle may be utilized for heating air whereby this heated air may be caused to circulate throughout the closed vehicle body during cold weather and likewise, be caused to circulate over the windshield and the windows of the vehicle body in order to serve to prevent frost formation thereupon.

It is an object of the present invention to provide a device of this character, which may be easily and readily installed upon motor driven vehicles with but slight alteration thereto and when installed, the air to be heated will be freely circulated through the same in order to supply pure heated air to the equipped vehicle body interior without coming in direct contact with the exhaust gases or interfere with the passage of the latter through the muffler portion thereof.

Other objects of the invention will be in part obvious and in part pointed out hereafter.

In order that the invention and its mode of operation may be readily understood by those skilled in the art to which it appertains, we have in the accompanying illustrative drawings, and in the detailed following description based thereupon, set out one possible embodiment of the invention.

In these drawings:

Figure 1 is a side elevation of the invention showing it installed upon a closed body type of motor driven vehicle.

Figure 2 is a vertical transverse section taken on the line 2—2 of Figure 1, looking in the direction in which the arrows point.

Figure 3 is an enlarged detail, partly in elevation and partly in longitudinal section illustrating the construction of the combined muffler and air heating device employed in connection with the invention.

Figure 4 is a transverse section taken on the line 4—4 of Figure 3, looking in the direction in which the arrows point.

Figure 5 is a fragmentary detail, partly in section, showing the arrangement of the fan

or aspirator in the air circulating means and the valve controlled device for individually or collectively operating the frost preventing and body heating portions thereof, and

Figure 6 is a detail in elevation showing the arrangement and the mounting of the fan or aspirator in the air circulating means, together with the motor for imparting rotary motion thereto.

Having more particular reference to the drawings, in connection with which like characters of reference designate corresponding parts throughout, it may be stated in a prefatory sense, that the invention hereinafter disclosed is particularly adapted for installation in motor driven vehicle bodies of the closed type. Hence, we have herein illustrated the invention as being installed upon a closed body type of motor driven vehicle generally indicated, for convenience, by the numeral 1.

The invention, per se, may be stated to comprehend an air circulating pipe or conduit, seamless or jointless throughout its length and designated by the numeral 2, said conduit having flexible or angularly disposed conduits 3 and 4 connected to the opposite ends of the same by suitable couplings 5.

Enveloping the major portion of the air circulating pipe 2 is a jacket or shell like casing indicated in its entirety by the numeral 6, said jacket consisting of a metal construction including cross sectionally semi-circular portions 7 and 8, certain of the marginal portions of which are flanged, as at 9, and are adapted to be arranged in complementary relationship, as is shown in the Figure 4, whereby bolts or other suitable fastening devices 10 may be passed therethrough and the cross sectionally semi-circular sections thus secured in jacketed relation about the air circulating pipe 2 in the manner as is clearly shown in the Figures 3 and 4. In this jacketed arrangement about the air circulating pipe 2, it will be noted that the device 7 is substantially circular in cross sectional shape, whereas the opposite end portions of the same are partially closed by end walls 11 having coaxially aligned openings therein through which the adjacent portions of the

95

85

75

80

65

70

55

opposite extremities of said pipe 2 extend, as is well shown in the Figure 4.

With a view toward providing the interior of the shell-like casing or jacket 6 with means for effecting the passage of heated exhaust gases from the vehicle motor through the same in a tortuous course and hence, insure their full contact with the exposed surface of the air circulating pipe 2, we form spiral webs 5 with each section 7 and 8 of the casing so that 10 upon connecting these sections together in the manner as is illustrated in the Figure 4, a continuous spiral baffle 12 will be extended or provided longitudinally through the interior of the jacket 6.

The opposite extremities of one of the sections of the jacket or shell like casing 6, and preferably, the section 8, is formed with openings communicating with short conduits or 20 elbows 13 and 14, the elbow 13 being adapted to receive therein the adjacent end of the exhaust manifold E of the equipped vehicle motor M, while the elbow 14 is preferably of a length to convey the exhaust gases from the 25 jacket 6 into the atmosphere.

The flexible or angular conduit or pipe 4, hereinbefore described, is preferably extended through an opening formed in the flooring of the vehicle body 1 into the same, as is shown 30 in the Figure 1; a cap like device 15 being engaged over the open end of said conduit and serving as a means for permitting the intake of air into said conduit from the vehicle interior and at the same time, as an effectual guard for said inwardly disposed end 35 of the conduit 4.

The flexible or angular conduit or pipe 2 is extended for a distance forwardly of the vehicle 1 and upwardly under the usual hood H thereof, whereat it is connected with a port 40 of a rotary fan casing 16, as indicated at 17, said fan casing being effectually supported upon the vehicle within the hood H and having a rotary fan or aspirator 18 mounted 45 therein, as is shown in the Figure 5. Another port is formed in the fan or aspirator casing 16 and has an elbow or conduit 19 extending therefrom, into which a Y-branch coupling 20 is engaged, one of the extremities of this Y- 50 coupling being angularly disposed and provided with substantially V-shaped end portions 21 having nozzles 22 connected to the extremities thereof. The remaining extremity of the Y-coupling is extended downwardly at 55 an angle from the elbow 19 and each of the extremities are adapted to be disposed through the forward wall of the vehicle body and to communicate with the interior thereof.

To permit of the selective control or regulation of the passage of air to and from the extremities of the Y-coupling 20, I pivotally mount within said coupling, as is shown in the Figure 5, a flap valve 23, fixedly securing to the pivot pin thereof, an operating lever 60 65 24, whereby pivotal movement may be con-

veniently imparted to said valve 23 and its positioning within the Y-coupling so regulated as to close one of the extremities of the same and to open the other or vice versa. Also, if desired, the flap valve 23 may be so arranged as to be neutrally positioned, that is, said valve may be adjusted so that it will divide or split the air passing from the elbow 19 into said Y coupling, and consequently upon this, the discharge of air from each of the extremities of said coupling will be effected.

As a means for imparting rotary motion to the fan or aspirator 18 within the casing 16, we extend the fan shaft from one of the bearings thereof, as is shown in the Figure 6, and connect the same to the rotary armature of an electrical motor 25, fixedly supported to an adjacent portion of the vehicle 1; suitable electrical conductors (not shown herein), being connected to the terminals of the motor and to the local source of energy of the vehicle (also not shown herein) for an obvious purpose.

In extending the V-shaped portions 21 of the upper of the extremities of the Y-coupling 20 into the vehicle body interior, it will be noted, especially, upon reference to the Figure 1, that the nozzle portions 22 are so positioned that they will discharge air passing therefrom onto the lower or middle portion of the inner side of the vehicle windshield. Because of this, the discharge from the nozzles 22 will be caused to deflect against the windshield and to cover a goodly portion of the area thereof before it passes rearwardly through the vehicle body in that port, as is indicated by the arrows in the Figure 1. Furthermore, it will be noted that with the opening or partial opening of the lower branch or extremity of the Y-coupling 20, the air will be passed from said extremity in that general course, as indicated by the arrows leading therefrom to the cap-like guard 15, also shown in the Figure 1.

In operation of our improved combined vehicle body heating and frost removing or preventing device, with starting of the motor M of the vehicle 1, heated exhaust gases will be passed through the exhaust manifold E into the forward end of the jacket 6 by way of the elbow 13. These heated exhaust gases will be caused to pass through the entire length of the jacket interior and by reason of the arranging of the baffles 12 therein, the coursing of these heated gases will be tortuous, hence, causing the same to have contact with the entire exterior area of the air circulating pipe 2 extending through said jacket 6, whereupon, the gases will then be discharged from the rearward end of the jacket 6 by way of the elbow or conduit 14 into the atmosphere. During this passage of the heated exhaust gases through the jacket 6, it will be understood that the air circulat-

ing pipe 2 will be heated thereby to a fairly high temperature.

Concurrently with the passage of the heated exhaust gases through the jacket 6, the aspirator 18 within its casing 16 is rotated from the electrical motor 25 in a direction to cause the in-taking of air by the guard cap 15 arranged adjacent the flooring of the vehicle body 1, as is shown in the Figure 1. This air will be drawn through the air circulating pipe 2 and consequently will be heated, whereupon it will be caused to pass from said pipe 2 to the flexible conduit 3 and the casing 16 and then discharged by way of the port or elbow 19 into the Y-coupling 20. By adjusting or positioning the flap valve 23 within said Y-coupling 20, this heated air may be caused to discharge from either of the extremities of said coupling, or from both thereof, as hereinbefore explained.

The heated air discharging from the nozzles 22 unto the inner side of the vehicle body windshield will serve as a means to positively remove frost formations therefrom, and also, to prevent such formations. Furthermore, by reason of this circulation of heated air by the windows of the vehicle body, it will be understood that the same will additionally serve as a means to remove such formations from the windows and will operate to prevent further formations of a similar character thereupon.

During summertime or warm weather, when it is not desired to discharge heated air into the vehicle body interior, the invention may be utilized as a means for cooling the heated exhaust gases discharging into the jacket 6 from the exhaust manifold E, hence, preventing overheating of the exhaust pipe. This latter expedient is accomplished by removing the free end of the conduit 4, which normally carries the guard cap 15 from the vehicle flooring and interior and permitting it to discharge outwardly of the vehicle body; also, by reversing the direction of rotation of the aspirator fan 18 so that it will serve as a form of injector, in taking air through the extremities of the Y-coupling 20 and passing said air by way of the conduit 3 downwardly into the communicating end of the air circulating pipe 2, and thence through the jacket 6, whereupon the air cooled pipe 2 will serve as a means for reducing the temperature of the heated exhaust gases discharged from the elbow 13 into said jacket 6.

Manifestly, the construction shown is capable of considerable modification and such modification as is within the scope of our claims, we consider within the spirit of our invention.

We claim:

1. A combined muffler and air heater comprising a cylindrical sectional casing, an air circulating pipe extending through said cas-

ing and arranged concentrically therewith, a plurality of spiral webs formed with each section of the casing, adapted to form a continuous spiral baffle extending around said air circulating pipe, and short conduits formed at the opposite ends of said casing for connection with the exhaust manifold of a motor, whereby the exhaust gases may be caused to travel through said casing around said air circulating pipe and subsequently be exhausted therefrom.

2. A combined muffler and air heater comprising a cylindrical shell-like casing consisting of two semi-circular sections, flanges formed with the side marginal portions of said sections and adapted to be arranged in complementary relationship, fastening elements adapted to extend through said flanges for connecting the sections together, end walls formed with said casing and having co-axial- ly alining openings therein, an air circulating pipe adapted to extend through said casing and said co-axially alining openings, spiral webs formed with each section of the casing adapted to form a continuous spiral baffle when the sections of the casing are connected together, short conduits formed at the opposite ends of one of said sections and provided for connection with the exhaust manifold of a motor whereby the exhaust gases therefrom may be caused to enter said casing and circulate about said air circulating pipe and be subsequently exhausted therefrom.

In witness whereof we have hereunto set our hands.
